US00D675190S

(12) **United States Design Patent**
Nylen

(10) **Patent No.:** **US D675,190 S**
(45) **Date of Patent:** **** Jan. 29, 2013**

(54) **SPEAKER**

(75) Inventor: **Tuomas Nylen**, Helsinki (FI)

(73) Assignee: **Nokia Corporation** (FI)

(**) Term: **14 Years**

(21) Appl. No.: **29/394,802**

(22) Filed: **Jun. 21, 2011**

(51) LOC (9) Cl. **14-01**

(52) U.S. Cl. **D14/215**

(58) **Field of Classification Search** D14/204,
D14/210–216, 172; 181/143–144, 147–148,
181/150–153, 157, 198–199; 381/300–303,
381/306, 332–333, 336, 345, 361–364, 386–388

See application file for complete search history.
